UNITED STATES PATENT OFFICE.

JAMES A. McKEEVER AND JAMES S. GRIFFIN, OF NEW YORK, N. Y.

FRANGIBLE PROTECTIVE HOOD.

1,227,467.

Specification of Letters Patent.

Patented May 22, 1917.

Application filed January 19, 1917. Serial No. 143,287.

To all whom it may concern:

Be it known that we, JAMES A. McKEEVER and JAMES S. GRIFFIN, both citizens of the United States of America, and both residing 5 in the city, county, and State of New York, have invented certain new and useful Improvements in Frangible Protective Hoods, of which the following is a specification.

Our invention relates to frangible protective hoods and particularly to hoods for protecting against theft or tampering articles of such nature that their utility requires exposure in accessible position but which should be left alone until emergency necessitates their use. Articles of this class are of various types, but we have in mind particularly, fire extinguishers, emergency switches, signal levers, etc., which must at all times be readily accessible for emergency use, but 10 need protection against theft or mischievous tampering in the exposed position in which their nature demands they shall be placed.

Referring to the accompanying drawings,

Figure 1 is a side elevation of a fire extinguisher over which our protective hood in one form is shown;

Fig. 2 is a plan view thereof, partially in section;

Fig. 3 is a broken elevation of portion of 30 the hood showing an improved fastening means therefor;

Fig. 4 is a side elevation of the fastening screw shown in Fig. 3;

Fig. 5 is a vertical section through the 35 hood arranged over an emergency switch;

Fig. 6 is a transverse section through a base showing a modified securing device for the hood.

Referring in the first place to hand fire extinguishers, which have gone into extensive and increasing use in buildings, shops and lately on automobiles, there has arisen the problem of protecting them against theft and mischievous tampering without interfering with their ready immediate accessibility for use in emergency. Fire extinguishers of this type are relatively small, and this fact, together with their value, has made them an easy subject of petty larceny. This 40 theft is not infrequently concealed by the replacing of the charged extinguisher by a used one, thus inducing a false sense of se-

curity, since the substitution is not readily observed without close scrutiny.

By the present invention we have provided a protective hood of frangible material which is so designed that it prevents the concealed theft of the extinguisher from its support, without in any way interfering however with its accessibility or preventing its quick removal for use.

In the form shown in the accompanying drawings, our invention comprises an elongated hood 10 of glass covering the body of the extinguisher and having side flanges 11 and 12 by which it may be secured to a supporting surface, for instance, a wall 13 by means of screws 14 passing through these flanges. The extinguisher here shown is a "pyrene" 15 and is supported upon the wall 16 by the usual lower and upper brackets 16 and 17 respectively. The lower bracket comprises a cup-shaped support 18 in which the lower end of the extinguisher rests with its nozzle 19 projecting through an aperture 75 therein. The upper bracket 17 comprises a spring fork 20, the legs of which straddle the stem 21 of the operating handle 22. It will be noted from Fig. 1 that the hood 10 extends over the body of the extinguisher and 80 prevents the removal thereof from its supports, but leaves exposed the handle 22, so that the latter may be readily grasped.

In order that the mounting may be secure, we propose to make the base flanges 11 and 12 of greater thickness than the hood 10, the latter being of such relatively light weight that it is easily broken when the pyrene is pulled free from the spring fork 20 by the hand which grasps the handle 22. To 85 cushion the hood and thus lessen liability to injury through vibration, pads 110 and 120 of felt or the like are interposed between the flanges and the support.

While ordinary screws 14 may be used to 95 secure the hood in position, we prefer to use the screw 23 shown in Fig. 4 in which the metal of the screw head is sheared off on opposite bevels on opposite sides of the slot 24, in such manner that while shoulders 25 100 are provided to form abutments for the end of the screw-driver on the insertion of the screw, no abutments are provided for the end of the screw-driver on the reverse rota-

tion of the latter. It is thus impossible, or practically impossible, to remove the screws 23 after they have been inserted. The possibility of theft by the removal of the hood 5 is thus minimized.

It is of course immaterial whether the extinguisher be mounted horizontally or vertically. Its manner of support is the same in any case and the hood 10 may be as readily 10 installed in one position as in the other. The securing of the hood in place is a matter of a very few moments' work. It is inexpensive and affords a protection against theft or mischievous tampering which has never 15 heretofore been afforded.

An additional element of value may be secured by applying to the interior of the hood, before it is installed, a paster 26 on which is written the date of the installation. 20 This affords ready means for disclosing to a proprietor or an inspector the age of the extinguisher and gives warning that a fresh extinguisher should be substituted. This is a feature upon which fire inspectors and 25 underwriters are more and more carefully insistent.

In Fig. 5 the hood is shown in connection with an emergency knife switch 27. The hood is so positioned that while the handle 30 28 is readily accessible for the operation of the switch, the switch cannot be opened without breaking the hood.

A modified arrangement for locking the hood in position is illustrated in Fig. 6, and 35 comprises a sheet metal locking plate 29 with end and side flanges, the longitudinal margin 30 being recurved to overlie the flange 12 on one side of the hood. This plate may be held in position by the screws 31 40 passing through the base 32 on which the article protected (not shown) is mounted. The opposite margin of the plate is slightly raised and provided with latching members 33. A coöperating locking plate 34 with re- 45 curved longitudinal margin 35, has corresponding latching members 36 which engage the members 33 when the plate 34 is slipped beneath the flange 11 of the hood to such position that the recurved margin 35 over- 50 lies the hood flange 11. It is obvious that when the hood and locking plates are in place the securing screws 31 are wholly concealed and inaccessible. Inasmuch as the latching elements are also concealed beneath 55 the hood flange 11, the hood is securely locked against removal. On the breakage of the hood, however, the hood flange 11 may be withdrawn from the recurved margin 35 of plate 34, and the edge of the plate 29 60 sprung away from the plate 34 thus freeing the latching members and permitting plate 34 to be withdrawn. After the adjustment of a new hood, the plate 34 may be again slipped into position and latched to lock the 65 hood against removal. This device affords

a more convenient means for renewing hoods than the one-way screws of Figs. 3 and 4.

We do not limit our invention to the particular form of the hood shown, or any particular means for locking it in protective 70 position, the underlying thought of our invention being to provide a ~~frangible~~ protective covering which must be broken on the use of the article to which it is applied and which is so shaped and arranged that it 75 does not interfere with the ~~immediate~~ accessibility of the article when it is needed for use. Various modifications will readily occur to those skilled in the art without departing from what we claim as our invention. 80

We claim as our invention:—

1. The combination with an exposed device, of a ~~frangible~~ hood incasing the body of said device to prevent removal or manipulation thereof, but leaving a portion of said device exposed for manual hold thereof, said hood being so arranged as to be unavoidably broken by the impingement against the inner face thereof of the device 90 on the manipulation or removal of the latter.

2. The combination with an article having a portion to be grasped on manipulation, of an independent ~~frangible~~ protective hood incasing said article but leaving said 95 manipulating portion exposed, said casing being so arranged that its inner face is unavoidably impinged against and fractured by the article on manipulation or removal of the latter.

3. A protective device of the type described, comprising an elongated ~~frangible~~ hood having base flanges on opposite sides thereof, together with means engaging said base flanges for securing the hood in position. 105

4. The combination with a body having an operating handle at one end thereof and a support at the opposite end thereof on which said body is pivotally carried, of a 110 ~~frangible~~ hood incasing said body to prevent removal or operation thereof but leaving the handle accessible for the removal of the body from its support, said hood being so arranged as to be unavoidably broken by 115 said body on its pivotal displacement from said support during the operation of removal.

5. A protective device of the type described, comprising an elongated ~~frangible~~ hood open at its ends and having base flanges on opposite sides thereof, together with means engaging said base flanges for securing the hood in position. 120

6. A protective device of the type described, comprising an elongated ~~frangible~~ hood open at its ends and having base flanges on opposite sides thereof, together with means engaging said base flanges for securing the hood in position, said flanges being 125 130

of greater strength than the body of the hood.

7. A protective device of the type described, comprising an elongated frangible hood open at its ends and having base flanges on opposite sides thereof, together with difficultly removable means engaging said base for securing the hood in position.

In testimony whereof we have signed our names to this specification, in the presence **10** of two subscribing witnesses.
